UNITED STATES PATENT OFFICE.

EDWARD BARNARD, OF ROME, NEW YORK.

HAME-CLIP.

SPECIFICATION forming part of Letters Patent No. 334,411, dated January 19, 1886.

Application filed November 3, 1885. Serial No. 181,770. (No model.)

To all whom it may concern:

Be it known that I, EDWARD BARNARD, a citizen of the United States, residing at Rome, in the county of Oneida and State of New York, have invented a new and useful Improvement 5 in Hame-Clips, of which the following is a specification, reference being had to the accompanying drawings.

My invention has relation to improvements 10 in hame-clips; and it consists of the peculiar construction and combination of parts, substantially as hereinafter fully set forth, and specifically pointed out in the claims.

My invention has for its object to provide a 15 hame-clip which shall not be liable to be withdrawn from engagement with the draft-eye of a hame when the device is in use; to provide for the easy and quick detachment of the clip from the hame draft-eye when it is desired to 20 change the character of the hame; to provide means whereby the clip can be easily and readily secured to the hame-tug and the draft-eye, and which shall present a neat appearance, and which shall be simple, strong, and 25 durable in construction, thoroughly effective in operation, and cheap of manufacture.

In the accompanying drawings, Figure 1 is 30 an elevation of my improved hame-clip in position upon an iron or metal hame and secured to the hame-tug. Fig. 2 is a like view of the clip secured to the draft-eye of a wood hame. Figs. 3 and 4 are detail detached views of the hame-clips for iron and wood hames shown in Figs. 1 and 2. Fig. 5 is a view of a hame- 35 clip having a detachable ball or cap-piece. Fig. 6 is a detail modification.

Referring to the drawings, in which like letters of reference indicate corresponding parts, A designates a hame of any ordinary construction, of either wood or metal; B, the draft-eye thereof; C, the hame-tug, and D my improved draft-eye rigidly secured to the hame-tug, and loosely or pivotally connected to the draft-eye of the hame.

Referring more particularly to Figs. 1 and 45 3, the hame-clip for a metallic hame comprises a flat shank, d, having two or more apertures, d', a rounded hook, d'', and a ball or sphere or cap, d'', on the extreme outer end 50 of the hook d''. The shank d is made flat, and is secured to the hame-tug by means of rivets

passing through the apertures d' thereof and the hame-tug, thus permanently securing the clip to the tug.

The hook cap, or ball, and shank are preferably formed or cast integral with each other, and the hook d'' is rounded and engages the draft-eye B of the hame; but, in lieu of casting the cap or sphere d'' with the hook, the outer end of said hook may be threaded, as at e, and 55 the cap or sphere d'' provided with a threaded socket, e', adapted to engage the threaded end of the hook. This construction is more fully shown in Fig. 5, and is employed when the hame-clip has been permanently secured 60 to the hame-tug and it is desired to disengage the clip from the draft-eye of the hame to change the character of the hame or substitute other forms therefor. The draft-eye B of a metallic hame extends outwardly therefrom at 65 a considerable distance, and the ball or the cap of the hame-clip may be fitted therein, as shown in Fig. 1, to project outwardly from the eye or lie on the inner face thereof, as 70 shown in Fig. 6.

In Figs. 2 and 4 of the drawings, the hame-clip is shown especially adapted for a wood hame; but the clip has the same essential characteristics features of the clip for metallic hames shown in the remaining figures of the drawings—*i. e.*, the shank d, the hook d'', and the cap or sphere d''. When the device is to be used on wood hames, which are especially used for heavy work, it is increased in the thickness of its parts to impart greater strength and 80 durability thereto. The hook d'' is made larger and thicker in cross-section, and preferably has a smaller degree of curvature, to more closely embrace or fit the draft-eye, and the cap or sphere of the hook is made larger and 85 stronger.

The clip shown in Figs. 2 and 4 may have the removable cap-piece, or cast integral or in one piece, and it is especially adapted to wood hames for heavy work or draft, while 95 the hame-clip for metallic hames is used for buggies and light work. This peculiar construction of hame-clip provides a free and loose joint between the hame-tug and draft-eye without any undue wear and strain on 100 said clip and eye. The ball or cap prevents any accidental disengagement of the clip and

eye, and presents a neat appearance, while it serves to provide a firm and secure coupling, and one which is simple, light, and strong.

To secure the device to the hame, the shank 5 is first passed through the draft-eye thereof and secured or riveted to the hame-tug, the hook d^2 of the clip engaging the draft-eye.

When the clip with the removable cap or ball is employed, it is removed from the hook 10 to permit the hame draft-eye to be detached or engaged therewith, and the cap or ball again secured on the threaded shank, to prevent the accidental detachment of the clip from the draft-eye.

Having thus fully described my invention, what I claim as new, and desire to secure by Letters Patent, is—

1. As an improved article of manufacture,

a hame-clip comprising a perforated shank, a hook formed integral with the shank and having a threaded end, and a removable cap or ball having a threaded socket to engage the hook, substantially as described.

2. As an improved article of manufacture, a hame-clip comprising a shank, an integral 25 curved hook at the front end thereof, and a detachable head at the outer end of the hook, substantially as described.

In testimony that I claim the foregoing as my own I have hereto affixed my signature in 30 presence of two witnesses.

EDWARD BARNARD.
